UNITED STATES PATENT OFFICE.

ARTHUR H. MALLOY, OF CHICAGO, ILLINOIS.

PROPELLING AND STEERING MECHANISM FOR AIR-SHIPS.

No. 857,949.

Specification of Letters Patent.

Patented June 25, 1907.

Application filed July 19, 1906. Serial No. 326,858.

To all whom it may concern:

Be it known that I, ARTHUR HENRY MALLOY, a citizen of the United States, residing at Chicago, in the county of Cook and State 5 of Illinois, have invented a new and useful Improvement in Propelling and Steering Mechanisms for Air-Ships, of which the following is a specification.

This invention relates to propelling and 10 steering mechanisms for air-ships and has for its object to provide improved apparatus of this class; and with this and other objects in view the invention consists in the construction, combination and arrangement of parts 15 to be hereinafter more specifically pointed out, described and claimed.

The invention is fully disclosed in the following specifications, of which the accompanying drawings form a part, and in which 20 the separate parts of my improvement are designated by suitable reference characters in each of the views, and in which—

Figure 1 is a side elevation of an air-ship with my propeller attachment. Fig. 2 is a 25 plan view of the same with the rudder attached. Fig. 3 is a side elevation showing the propeller turned at an angle with the body of the air-ship. Fig. 4 is a plan view of the invention showing the propeller elevated 30 at an angle with the body of the air-ship.

Like numerals of reference indicate like parts in the several views.

The numeral 2 indicates an air-ship frame of ordinary construction to which the propelling mechanism is attached.

Referring now to the propelling mechanism, the numeral 3 indicates a motor carried by the cross rods 4 which connect the lower horizontal rods of the frame. 40 5 indicates a sprocket-wheel carried by the motor and connected by a chain with sprocket-wheel 6, said sprocket-wheel being arranged on the connecting shaft 7 which is journaled in the end 8 of the air-ship frame 45 work. The end of the connecting shaft carrying the sprocket-wheel is journaled in the supporting-frame 9 which frame comprises a cross piece extending from side to side of the lower framework of the air-ship and a vertical portion perpendicular to the cross piece 50 and extending from the same to the upper horizontal portion of the air-ship frame. The end of the connecting shaft journaled in the air-ship frame is bifurcated as at 10

and a pivot connects the two branches of the 55 same. A block 12 is arranged to turn upon said pivot. Another pivot extends through block 12 at right angles to the first pivot and connects the prongs of the bifurcated auxiliary shaft 13. Block 12 with the two pivots 60 forms a coupling for the connecting shaft 7 and the auxiliary shaft 13. The end of the air-ship carrying the propeller blades is provided with a supplementary framework 14 welded thereto for the purpose of supporting 65 part of the propelling mechanism. Said supplementary framework is of suitable shape and provided at its free extremities with eyes 15, for holding in position the hub 16, upon which part of the propelling mechanism 70 swings. The eyes 15 engage pins 17 protruding from said hub. The hub 16 is further provided with pins 18 which engage the eyes 19 of the swinging frame 20, in the bearing of which is journaled the auxiliary shaft 75 13 carrying on its free extremity the propeller hub 21 to which the propeller blades 22 are attached.

Referring now to supporting frame 9, the same is provided with an upright 23 to which 80 is pivoted a lever 24, the said lever 24 having an arm 25 pivoted thereto, the other extremity of said arm being pivoted to an upright 26 welded to the hub 16 thus forming a means 85 for swinging said hub on its pins resting in the supplementary framework 14. It is readily seen that since the swinging frame is attached to hub 16 and the auxiliary shaft 13 carrying the propeller blades is journaled in 90 said frame, the inclination of the hub 16 will raise or lower the propeller blades with reference to the body of the air-ship. Another upright 27 is arranged on the supporting frame 9 and pivoted to its upper extremity is another lever 28 having an arm 29 pivoted 95 thereto, the opposite extremity of said arm being pivoted to an auxiliary arm 30 having its opposite extremity welded to the rudder 31 which is arranged on the rear end of the air-ship which is understood to be the end 100 most distant from the propeller blades. A lever-rack 32 extends from the upper horizontal rod of the air-ship frame and is provided with notches 33 for the retention of the levers when placed in the same. In this 105 manner the propeller blades or the rudder may be elevated or depressed with relation to the air-ship and held at any desired angle.

with the body of the same. Between the motor and the rudder I provide a steering wheel 34 supported on a suitable sub-frame and provided with a lever 35 for turning said wheel. The periphery of said wheel is grooved to carry a guide rope 36 which rope extends from said wheel toward the front of the air-ship, through the eyes 37 of the cross-rod 38, (which rod is for the purpose of keeping the guide rope out of the way of the body of the air-ship) and is connected with hooks 39 which engage the ears 40 of the swinging frame. By means of the steering wheel it will be seen that the propeller blades and support therefor can be turned from left to right or vice versa and so guide the ship in its course.

Operation: When the motor is turned on the sprocket-wheel carried thereby revolves and imparts motion to the sprocket-wheel located on the connecting shaft which turns said shaft and by means of the coupling between the connecting shaft and the auxiliary shaft the latter is also caused to revolve in its bearings and as the propeller hub is fixed to the free end of the auxiliary shaft it revolves together with the propeller blades and in this manner the air-ship is propelled. The motion of the air-ship can be reversed by reversing the motor. The rudder is intended to facilitate the upward or downward flight of the ship by inclining it in the direction in which travel is desired. It is understood the air-ship is to be provided with a balloon of suitable dimensions for the purpose of "floating" the ship.

Having thus described my invention, what I desire to claim as new and secure by Letters Patent is—

40 1. In a propelling mechanism, a motor, a sprocket-wheel carried thereby, a connecting shaft suitably supported and carrying a sprocket - wheel engaging the aforesaid sprocket-wheel, an auxiliary shaft coupled to said connecting shaft, propeller blades arranged on said auxiliary shaft, a hub 16 carried by supplementary framework of the air-ship, a swinging frame pinioned to said hub and carrying said auxiliary shaft in its bearings.

45 2. In an air-ship, a propeller comprising a motor, a sprocket-wheel carried thereby, a connecting shaft arranged directly above said motor and carrying a sprocket-wheel to engage the aforesaid sprocket-wheel, an auxiliary shaft coupled to said connecting shaft, propeller blades carried by said auxiliary shaft, a swinging hub carried by supplementary framework of the air-ship, a swinging frame pinioned to said hub and having said

auxiliary shaft journaled therein and means for inclining said swinging hub to any angle desired.

3. In an air-ship, a propeller comprising a motor, a sprocket-wheel carried thereby, a connecting shaft running longitudinally of the air-ship and carrying a sprocket-wheel on one extremity for engaging the aforesaid sprocket-wheel, an auxiliary shaft coupled to said connecting shaft, propeller blades arranged on said auxiliary shaft, a swinging hub carried by supplementary framework of the air-ship, a laterally swinging frame pinioned to said hub, an upright welded to said hub, an arm pivoted to said upright, a lever connected to said arm and a lever-rack carried by the upper framework of the machine for retaining said lever when at rest.

4. In an air-ship, a steering apparatus comprising a steering wheel and suitable supporting frame therefor and a controlling lever carried by said wheel, a cross rod carried by the framework of the machine and having eyes in its extremities, a laterally swinging frame supported at the front end of the air-ship and designed to steer it horizontally, ears carried by said swinging frame, a guide rope extending from the steering wheel, passing through the eyes of the cross rod and terminating in said ears.

5. In an air-ship, a steering apparatus comprising a steering wheel, a laterally swinging frame pivoted on the front of the air-ship, a guide rope connecting said steering wheel and swinging frame, a rudder arranged on the rear of the ship and means for raising or lowering the same to facilitate the upward or downward motion of the air-ship.

6. In an air-ship, a steering apparatus comprising a steering wheel and lever therefor, a laterally swinging frame pivoted to the front framework of the air-ship, means connecting said frame and steering wheel, a rudder arranged on the rear of the air-ship, an auxiliary arm welded thereto for raising or lowering said rudder, a connecting arm pivoted to said auxiliary arm, a lever carried by the framework of the air-ship and pivoted to said connecting arm and a lever-rack extending from the upper framework of the air-ship and designed to engage the said lever when the same is at rest.

In testimony that I claim the foregoing as my own, I have hereto affixed my signature in the presence of two witnesses.

ARTHUR H. MALLOY.
